his Attorneys.

UNITED STATES PATENT OFFICE

HARRY W. HELMS, OF DETROIT, MICHIGAN, ASSIGNOR TO HIGHWAY TRAILER COMPANY, OF EDGERTON, WISCONSIN, A CORPORATION OF WISCONSIN

COVER FOR DUMP BODY VEHICLES

Application filed May 9, 1931. Serial No. 536,106.

This invention pertains to vehicles having a laterally tilttable dump body especially designed for refuse collection and similar work, and more particularly the present invention relates to means for enclosing the load-carrying space of the body. The main object of this invention is to provide an improved cover construction that is comparatively simple, light in weight and which may be quickly and easily manipulated for movement to and from operative position. Another object is to provide an improved cover of this character which is mounted independently of the body and is composed of a plurality of independently movable cover sections adapted to be nested in telescoped relation at either side of the body so as to permit unhampered movement of said tilting body in opposite direction for discharging its load. A further object is to provide an improved cover construction having a plurality of independently movable cover sections arranged for exposing a limited portion of the load-carrying space of the body at will. The invention consists in certain elements and features of construction in combination, as herein shown and described, as indicated by the claim.

In the drawings:

Figure 1 is a view in side elevation of a cover embodying the present invention; the view being broken for condensation at one side of the break showing the cover in closed position while at the other side showing the cover sections telescoped one in another to expose a portion of the load-carrying space of the body.

Figure 2 is an end view of the vehicle provided with my improved cover construction with the cover shown in closed position, and is taken substantially as indicated at line, 2—2, on Figure 1.

Figure 3 is a detail transverse section taken substantially as indicated at line, 3—3, on Figure 2.

Referring now in detail to the drawings, the vehicle chosen for illustration is of conventional design and includes the usual upwardly open hopper body, 5, carried on curved rockers, 6, which are mounted for movement on transversely extending rails, 7,

secured to the vehicle main frame, 8. These rockers which are formed about a comparatively large radius support the body and are arranged to permit the body to be rolled laterally to either side for discharging its load. 55 The cover for the body is mounted independently thereof so as not to alter its normal center of gravity and, as will hereinafter appear, said cover is so designed and arranged for movement to a position at which the body 60 may have free and unobstructed dumping action. It is to be understood that the body is normally locked in upright position to the frame by any suitable locking mechanism.

The cover as seen in the drawings is composed of a plurality of sections, and more particularly two arcuate sections normally extending longitudinally over opposite portions of the load-carrying space of the body, 5, in closed position, and adapted to be telescoped 70 one within the other or one over the other in opening; and for convenience they may be termed outer section, 10, and inner section, 11. The outer cover section, 10, is formed about a radius slightly larger than the inner section, 11, to afford proper clearance between them in their telescopic movements. Each cover section is provided with a skeleton frame, 12, of any suitable light weight construction, to which is secured a light weight 80 covering, 13, such as canvas, or the like, or even light weight sheet metal. The cover sections are each provided with supports at the ends of the body, which may consist of single members, or as herein shown as several 85 radially extending supporting members, 14. The supporting members of the outer section are secured to a plate, 15, which is pivotally supported in a mounting bracket, 16, secured to a cross member, 17, on the main frame, 8. 90 The supporting members of the inner section are positioned nearer the body than the members of the outer section, and are connected to a plate, 18, which is coaxially pivoted with plate, 15, in the bracket, 16, between said plate, 15 and the body. Since the cover sections swing about a common pivot or center, they travel in true arcs and insure proper telescoping relation to each other so as to permit either cover section to be freely moved to

the opposite side of the body. Due to the pivotal support for these cover sections being substantially central with respect to the body, the cover sections are necessarily unbalanced and normally tend to assume positions over either side of the body as clearly shown in the drawings.

The respective cover sections, 10 and 11, are designed so as to extend beyond the center of the body when in closed position, resulting in a partial overlapping of the outer cover section, 10, on the inner section, 11, and providing an effective closure. The ends of each cover section are also enclosed by sheet material, 19, preferably the same as the top, 18, extending somewhat below the edges of the body.

These cover sections are supported in closed position or limited in their extreme opening movements by stop brackets, 20, on the main frame, 8, adjacent the ends of the body, engaging the supporting members, 14, of said cover sections, as may be seen in the drawings. Both of the cover sections are arcuately formed with a radius large enough, so that when the covers are both telescopically positioned on either side of the body, said body may clear the cover sections as it is rolled laterally (to the side opposite said covers) to discharge its load; the path of travel of an edge of the body in one direction being indicated by dotted lines in Figure 2.

In the present construction either cover section may be quickly and easily pushed to the opposite side of the body to uncover a portion of its load-carrying space. It will be understood that more than two telescopically arranged cover sections may be employed without departing from the spirit and scope of my invention.

I claim:

In combination with a vehicle having a main frame, an upwardly open laterally tiltable dump body mounted thereon, the main frame having transversely extending track rails for supporting the dump body and the dump body having supporting rockers by which it is mounted on said track rails for rocking transversely in lateral dumping; a cover for the body comprising two arcuate sections adapted to be telescoped with each other in the direction of their arcuate extent, and for that purpose having radial supports by which they are pivotally mounted on the main frame for swinging over the pivot axis substantially in the path of their arcuate form, the radius and length of said radial supports exceeding the dimension of the dumping body from the upper edge of either side thereof to the point on the circumference of the rocker at the opposite side which is rocked into contact with the track rail at the extreme dumping position of the dump body, whereby when one of said arcuate sections is telescoped with the other at the normal

position of the latter for uncovering the dump body at one side, the dump body rocked for dumping at that side, swings clear of the two telescoped cover members.
